UNITED STATES PATENT OFFICE.

AMOS F. GERALD, OF FAIRFIELD, MAINE, ASSIGNOR TO HIMSELF AND
ELBRIDGE G. RIDEOUT, OF NEW YORK, N. Y.

SEWING-MACHINE NEEDLE.

SPECIFICATION forming part of Letters Patent No. 248,158, dated October 11, 1881.

Application filed January 15, 1881. (No model.)

To all whom it may concern:

Be it known that I, AMOS F. GERALD, of 5
Fairfield, in the county of Somerset and State
of Maine, have invented a new and useful Im-
provement in Sewing-Machine Needles, of
which the following is a full, clear, and exact
description.

Figure 1 is a side elevation of my improve-
ment. Fig. 2 is a sectional elevation of a part
10 of the same. Fig. 3 is a cross-section of the
same, taken through the line *x x*, Fig. 2, look-
ing upward.

Similar letters of reference indicate corre-
sponding parts.

15 The invention consists in combining with a
body having a slit, pin, and eye, an inclined
splint having its upper end set outwardly, and
a sleeve inclined at the inside of its lower end,
having opposite notches on its lower edge, and
20 a slot, as hereinafter described.

A represents a sewing-machine needle, which
is secured to the needle-holder of the machine
in the ordinary manner. In the needle A is
25 formed a slit, B, extending from a little below
the eye C along one side of the said eye, and
upward to some point above the part of the
needle that passes into the goods, where it
passes out at the side of the needle, as shown
30 in Figs. 1 and 2.

The inclined or tapered upper end of the splint
35 D, formed by the slit B, is sprung or set out-
ward a little, so that when the said splint is
left free a thread can be inserted between the
body A of the needle and the end of the splint
40 D and slipped down through the slit B to the
eye C.

The upper end of the splint D is held in place
against the body A of the needle by a sleeve,
E, or other guard. The inner surface of the
45 part of the sleeve E that passes over the end
of the splint D is inclined, so that it will pass
over the said end and press and hold it close
to the body A of the needle. In the opposite
50 sides of the lower edge of the sleeve E are
formed notches or recesses F to receive the
thread when it is drawn across the splint D and
pressed upward. The movement of the sleeve
E is limited by a pin, G, passing through a slot,
H, in the said sleeve, and into the body A of the
needle, as shown in Fig. 2. The guard E may
be held down by its own weight, or it may be

pressed down by a spring connected with the
needle-holder. The guard E may also be con-
nected with and supported from the needle-
holder.

The guard E has been shown and described
as made in the form of a sleeve, and this con-
struction I prefer as being neat, simple, and
effective; but it may be so made as to pass only
part way around the needle, or it may be made
60 in the form of a lever or cam connected with
the needle-holder, and arranged to cover and
protect the point or upper end of the splint D.

The advantage of connecting the guard E
with the needle-holder is that in that case only
65 one guard will be required for each machine
instead of having a guard for each needle, as
is necessary when the guard is permanently
connected with the needle.

In threading a needle provided with my im-
provement the operator takes hold of the thread
I with the thumbs and fingers of both hands,
and with his hands at a little distance apart,
and draws the part of the thread I between his
hands across the splint D, and presses it up-
70 ward against the lower edge of the guard E,
so that the thread I will slightly raise the said
guard E, enter the recesses F, and pass over
the point of the splint D. The thread I is then
drawn downward through the slit B until it en-
75 ters the eye C. With this improvement the
needle can be threaded very easily and quickly,
even by those having imperfect eyesight. The
extension of the slit B below the eye C allows
the splint D to spring outward as the thread
80 passes downward to the eye C more easily and
gradually, and with less danger of breaking
than if the said slit B stopped at the eye C.

Having thus described my invention, I claim
as new and desire to secure by Letters Patent—
85

In a sewing-machine needle, the combina-
tion, with the body A, having slit B, pin G,
and eye C, of the inclined splint D, having its
upper end set outwardly, and the sleeve E, in-
90 clined at the inside of its lower end, and having
opposite notches, F, on said lower edge, and the
slot H, to adapt the needle to be used as
described.

AMOS F. GERALD.
